UNITED STATES PATENT OFFICE

EDWARD E. BARTELS, OF WHITING, INDIANA, ASSIGNOR TO STANDARD OIL COMPANY,
OF WHITING, INDIANA, A CORPORATION OF INDIANA

ART OF CONVERSION OF HYDROCARBON OILS

Application filed November 29, 1926. Serial No. 151,446.

The present invention relates to improvements in the art of conversion of high boiling hydrocarbon oils into lower boiling point hydrocarbon oils such as gasoline or the like, and will be fully understood from the following description, illustrated by the accompanying drawings, in which:

Figure 1 is a side elevation, showing diagrammatically apparatus for carrying the invention into effect;

Fig. 2 is a sectional view taken as indicated at line 2-2 of Fig. 1;

Fig. 3 is a section taken as indicated at line 3-3 of Fig. 2;

Fig. 4 is a section taken as indicated at line 4-4 of Fig. 2; and

Fig. 5 is a section taken as indicated at line 5-5 of Fig. 2.

Referring more particularly to the drawings in Fig. 1, the numeral 6 indicates a pipe still or heating coil to which oil is supplied under pressure through the line 7. In the pipe still 6 the oil is brought to a conversion temperature above 700° F. or higher and preferably to a temperature of 800° to 850° F. although temperatures as high as 950° to 1000° F. may be employed. The oil is discharged from the pipe coil 6 before extensive conversion thereof has taken place, the rate of flow being such as to prevent any substantial coke or carbon deposition within the pipes. From the pipe coil 6 the heated oil passes through a line 8 into a chamber 9. From chamber 9 the oil passes through overflow lines 10 and through distributing means in chambers 11 and 12, which means will be described in detail hereinafter, into chambers 11, 12 and 13. If desired, mild heat may be supplied to the chambers so that no very substantial drop of temperature will take place therein. In the chambers the heated oil is retained at conversion temperatures of 700° to 850° F. until a substantial further conversion into light products, such as gasoline, has taken place. Each of the chambers 9, 11, 12 and 13 is provided with a valved draw-off line 14 through which unvaporized oil may be withdrawn. From the chambers, vapors pass out through vapor lines 15 into a common vapor manifold 16

which leads to the lower portion of a dephlegmating tower 17.

Reflux formed in tower 17 is discharged from the base of the tower to the line 18 and is forced by pump 19 through line 20 into the line 7 leading into the pipe still 6. Vapors heavier than the desired distillate product are condensed within the dephlegmator 17, the cooling action being aided by a suitable reflux cooling coil 21 provided in the upper portion of the dephlegmator 17, the cooling medium being supplied thereto through the pipe 22 and leaving the dephlegmator, somewhat preheated, through the line 23. Oil of a character suitable to be charged into the system is preferably used as a cooling medium in the upper portion of the dephlegmator, and therefore line 23 is extended to communicate with the inlet line 7 of the pipe still 6.

From the dephlegmating tower 17, the vapors of the desired low boiling products pass out through line 24 to a condenser 25, from which the condensate and cool vapors pass, preferably through a pressure reducing valve 26, into the receiver 27. From the receiver 27 the liquid product may be drawn off through the line 28 and vapors escape through the line 29 into a pressure gas line 30, which may be connected with a low pressure gas line 31 by a suitable controllable release valve 32. A pressure of four atmospheres or higher, preferably 250 to 500 pounds is maintained upon the system.

As will be apparent from Figs. 2 to 5, inclusive, chambers 11 and 12 are provided with receptacles or pans 33 which receive the oil flowing from chamber 9. Although the pans 33 may be of any desired size or shape, it is preferred to have them so constructed as to extend across a portion of the cross section of each chamber, each pan having a curved side 34 conforming in shape to the wall of the chamber and apertured at 35 to receive the overflow pipes 10, and having also a side 36 extending across the chamber. A segment of the cross section of the chamber is thus left open through which free communication between the lower and upper parts of the chamber is established. The pan in chamber 12 is

also provided with a partition 37 dividing the pan into two compartments 37^a and 37^b. Compartment 37^b communicates through the overflow line 10 with chamber 11 and compartment 37^a communicates with chamber 13. The oil received in the pan of chamber 11 and compartment 37^b of chamber 12 may be discharged into chambers 11 and 12, respectively, and, through compartment 37^a, into chamber 13 in any desired proportions by means of suitable perforations or openings 38 preferably circular, in the pan and compartment walls 36 and 37. The oil normally stands at a level substantially above the opening in the 15 pans. By varying the size, shape or area of the openings 38, the rate of flow of the oil may be distributed as desired among the several chambers. In practice, it is preferred to distribute the oil received in the pans approximately equally among chambers 11, 12 and 13. Unvaporized oil in the chambers may be withdrawn from each or all of the chambers through valved draw-off lines 14. In the preferred operation of the apparatus, 20 the unconverted oil is withdrawn from chambers 11, 12 and 13 and at such regulated rates as will prevent overflow from any one of these chambers into pans 33 and the other chambers; and in the practice in which the oil is distributed approximately equally among chambers 11, 12 and 13, the unvaporized oil is ordinarily withdrawn therefrom at substantially equal rates. The distributing means, herein described in connection with 25 four chambers, may obviously be used with any number of chambers and, if desired, may be employed to distribute charging stock in the first chamber 9 at the same time that the oil is distributed among the remaining chambers.

In the operation of the process in which oil is passed from chamber 9 by means of overflow lines through chambers 11, 12 and 13 successively, it has been found that after the 45 period of time the accumulation of coke and tarry matter is much greater in the end still 13 or stills 12 and 13, than in the other stills and that further operation of the apparatus is thereby prevented. By distributing the oil, in accordance with this invention, substantially equally among stills 11, 12 and 13, the coke and tarry matter accumulations are found to be about the same in each chamber, their character is so changed as to substantially decrease the quantity of dense coky matter accumulated, and the length of the runs has been substantially increased.

It is not intended that the details of apparatus illustrated nor of the process as above set forth, shall be regarded as limitations upon the scope of the invention, except in so far as included in the accompanying claims.

I claim:

1. The method of producing low boiling point hydrocarbon oils in the gasoline range

of boiling points from higher boiling hydrocarbon oils which comprises passing the higher boiling oil in continuous flow through a heated zone in which it is brought to conversion temperature, maintaining separate bodies of oil in a plurality of enlarged chambers at conversion temperatures, passing the heated oil into said separate bodies of oil and discharging oil therefrom into said enlarged chambers, while maintaining pressure upon the oil throughout the system, whereby substantial conversion takes place therein, and withdrawing unvaporized oil from the chambers.

2. The method of producing low boiling point hydrocarbon oils in the gasoline range of boiling points from higher boiling hydrocarbon oils which comprises passing the higher boiling oil in continuous flow through a heated zone in which it is brought to conversion temperature, then passing the heated oil at conversion temperatures into one of a plurality of connected enlarged chambers, maintaining separate bodies of oil in a plurality of the remaining chambers, passing the heated oil from said first-mentioned chamber into said separate bodies of oil and discharging oil therefrom into said chambers, while maintaining pressure upon the oil throughout the system, whereby substantial conversion takes place therein and withdrawing unvaporized oil from the chambers.

3. The method of producing low boiling point hydrocarbon oils in the gasoline range of boiling points from higher boiling hydrocarbon oils which comprises passing the higher boiling oil in continuous flow through a heated zone in which it is brought to conversion temperature, then passing the heated oil at conversion temperatures into one of a plurality of connected enlarged chambers and distributing oil from the upper portion of said chamber in substantially equal amounts among the remaining chambers, while maintaining pressure upon the oil throughout the system, whereby substantial conversion takes place therein and withdrawing unvaporized oil from the chambers.

4. In apparatus for the conversion of hydrocarbon oils, a heating coil, means for forcing oil therethrough, means for heating the oil therein to conversion temperature, a plurality of enlarged chambers maintained at conversion temperature, means for maintaining separate bodies of oil in a plurality of said chambers, means for supplying thereto said heated oil, and means for discharging oil from said separate bodies of oil into said chambers.

5. In apparatus for the conversion of hydrocarbon oils, a heating coil, means for forcing oil therethrough, means for heating the oil therein to conversion temperature, a plurality of enlarged chambers maintained at conversion temperature, means for discharging

ing the heated oil into one of the chambers, means for maintaining separate bodies of oil in a plurality of the remaining chambers, means for supplying thereto oil from said first-mentioned chamber, and means for discharging oil therefrom into said remaining chambers.

6. In apparatus for the conversion of hydrocarbon oils, a heating coil, means for forcing oil therethrough, means for heating the oil therein to conversion temperature, a plurality of enlarged chambers maintained at conversion temperature, means for discharging the heated oil into one of the chambers, and means for distributing oil received from said chamber among the remaining chambers, said means comprising overflow pipes between the chambers, pans receiving oil from the overflow pipes, and openings in the sides of the pans through which oil discharges into the chambers.

7. In apparatus for the conversion of hydrocarbon oils, a heating coil means for forcing oil therethrough, means for heating the oil therein to conversion temperature, a plurality of enlarged chambers connected by overflow lines, means for discharging the heated oil into one of the chambers, pans in the intermediate chambers receiving oil from the overflow pipes, a partition in the pan of the chamber next to the last, and openings in the sides of the pans and in the partition, permitting a discharge of the oil into the intermediate and last chambers.
